UNITED STATES PATENT OFFICE.

CHARLES MILLER, OF BINGHAMTON, NEW YORK.

SECTIONAL CUSHION-TIRE.

SPECIFICATION forming part of Letters Patent No. 735,993, dated August 11, 1903.

Application filed September 29, 1902. Serial No. 125,247. (No model.)

To all whom it may concern:

Be it known that I, CHARLES MILLER, a citizen of the United States, residing at Binghamton, in the county of Broome and State 5 of New York, have invented certain new and useful Improvements in Sectional Cushion-Tires, of which the following is a specification.

This invention relates to wheels having sectional cushion-tires; and it consists in certain improvements in the construction of such tires, as hereinafter described and claimed.

In the accompanying drawings, Figure 1 is a perspective view of a portion of a wheel-rim embodying the features of my invention. Fig. 2 is a longitudinal section through the same, showing my cushion-tire with the core of sponged rubber cured into the outer casing, so as to form one piece with it. Fig. 3 is a section on the line 3 3 of Fig. 2. Fig. 4 is a detail view of one of the T-bolts. Fig. 5 is a perspective view of a modified form of my invention as adapted for a regular or crescent wheel-rim, such as is in general use for pneumatic tires, showing a crescent-shaped strip of wood on which the sections of my cushion-tires are to rest. Fig. 6 is a longitudinal section through the same. Fig. 7 is a section on the line 7 7 of Fig. 6. Fig. 8 is a detail view 30 of the T-bolt used in the construction shown in Fig. 5. Fig. 9 is a detail perspective of still another modification. Fig. 10 is a detail section thereof, and Fig. 11 is a detail perspective view.

Referring to the drawings, A designates a channeled wheel-rim on which is mounted one section of my cushion-tire.

B indicates the outer casing of a section of my rubber tire with a bead or flange I at its 40 base.

C indicates a sponged-rubber core that is cured into the outer casing, so as to form one piece with it. The curing is done in the following manner: The outer casing is built up 45 of fabric and rubber with a bead at its base. It is then put into the mold and semicured. The iron core that is in the outer casing when it is semicured is then removed from the outer casing and sponge-rubber is put in its place.

The mold is put back in the vulcanizer and finished curing or the outer casing may be 50 built up of fabric and rubber with a bead at

its base and the sponge-rubber placed inside of it and put into the mold and all cured together. In either case the core or sponge 55 rubber placed inside is cured into the outer casing, so that it cannot be removed, or, in other words, it is all in one piece with the outer casing.

D indicates the half-caps in the channeled 60 rim. These half-caps (or divided cap) cover or press each side of the sections E and force them down into the channel of the rim, which channel holds the half-caps together on the sections.

F indicates the T-bolts that draw the half-caps down onto the flanges of the rubber sections and into the channeled rim.

G (shown in Fig. 5) indicates a strip of wood, crescent-shaped, which fits into the crescent 70 rim H and makes a flat surface on which to rest my sections of tire when it is desirable to use them on wheels having crescent-shaped rims.

The caps or half-caps D rest on the flanges 75 I of the sections E, while at each end of the caps the T-bolts F rest on and draw them down into the rim and also prevent them from breaking apart. The caps may be either in one piece or in two pieces, (half-caps,) as desired.

In Fig. 9 a design is shown for heavy vehicles. The half-caps are used, and each half-cap has a half circle or square K cut out at its ends; which when fitted to the end of the 85 half-cap of the corresponding section form holes or eyes for the bolts to go through to draw the caps down on the flanges of the sections. L indicates a plate having holes or eyes M, corresponding to those in the ends of 90 the half-caps, which plate is designed to rest on the ends of the half-caps, and bolts N go through this plate and through the holes or eyes in the ends of the half-caps and draw them down onto the flanges of the sections 95 and into the channeled rim. N indicates the bolt passing through the plate and the ends of the half-caps, and O indicates the nut by which said bolt is made fast to the inner periphery of the wheel-rim. A different construction of a T-bolt is shown on Fig. 8, with ends P adapted to prevent the half-caps from falling apart and to draw the sections down onto the base of the rim.

I claim—

1. The combination with a channeled rim, of a cushion-tire fitted therein and made up of independent sections, each of which has 5 end and side flanges within the rim, open caps snugly embracing the respective tire-sections and resting against the flanges with their abutted ends provided with registered notches, and T-bolts passing through the openings 10 formed by the registered notches and also piercing the rim, the heads of the bolts overlapping the abutted ends of the caps.

2. The combination with a channeled rim, of a cushion-tire fitted therein and made up 15 of independent sections, each of which has opposite end and side flanges within the rim, open caps snugly embracing the respective tire-sections and bearing upon the flanges thereof with their abutted ends provided with 20 registered notches, each cap being formed in opposite longitudinal sections with the joint therebetween intersecting the notches at the ends of the cap, and T-bolts passing through the openings formed by the notches and also 25 piercing the rim, the heads of the bolts lying transversely of the rim and overlapping the abutted ends of the caps.

3. The combination with a channeled rim, of a cushion-tire fitted therein and made up 30 of independent sections, each of which has opposite end and side flanges within the rim, open caps snugly embracing the tire-sections and bearing upon the flanges thereof with their abutted ends reduced in thickness and 35 provided with registered notches, and T-bolts passing through the openings formed by the registered notches and piercing the rim, the heads of the bolts being disposed transversely of the rim and seated snugly in the seats 40 formed by the reduced abutted ends of the caps.

4. The combination with the crescent rim of a wheel of a crescent-shaped strip of wood, adapted to fit into said crescent-shaped rim, 45 sections of cushion-tire with resilient centers cured into them and resting on said strips of wood, caps—either in one piece, or divided to form half-caps, resting on the flanges of the sections, T-bolts resting on the ends of said 50 caps and drawing them down onto the flanges of said sections and into the crescent rim.

5. The combination with a channeled rim,

of a strip fitted therein and provided with a flat outer face, a cushion-tire fitted in the rim and made up of independent sections resting 55 against the flat face of the strip, each section having opposite end and side flanges within the rim, individual caps resting against the respective tire-sections and having central openings through which the bodies of the tire-sections project, and T-bolts extending between the opposite ends of the adjacent caps and piercing the rim, with the heads of the bolts lying transversely across the rim and overlapping the ends of the caps. 60

6. A tire, embodying a casing having its opposite longitudinal edges formed for connection with a rim, and a sponge-rubber core cured into the casing. 65

7. A tire embodying a casing made up of fabric and rubber, with its opposite longitudinal edges formed for connection with a rim, and a sponge-rubber core cured into the casing. 70

8. The combination with a rim, of a cushion-tire made up of independent sections, 75 caps embracing the respective sections, and formed in longitudinal sections, and T-shaped fastenings having their heads overlapping the ends of the sections and their stems secured to the rim to hold the caps in place. 80

9. The combination with a rim, of a cushion-tire made up of independent sections, caps embracing the respective tire-sections and formed in longitudinal sections, the abutted ends of the adjacent caps being reduced 85 and notched, and fastenings, consisting of heads fitted in the seats formed by the abutted, reduced ends of the caps, and stems passing through the notches and the rim.

10. The combination with a channeled rim, 90 of a strip fitted snugly in the rim and provided with an outer flat face, a tire fitted flat against the strip and made up of independent sections, caps embracing the respective tire-sections, and headed fastenings piercing the 95 rim and the strip with their heads engaging the ends of the caps to hold the same in place.

In testimony whereof I affix my signature in presence of two witnesses.

CHARLES MILLER.
